UNITED STATES PATENT OFFICE.

CLARK D. PAGE, OF ROCHESTER, NEW YORK, ASSIGNOR OF ONE-HALF TO
DE WITT C. ELLIS, OF SAME PLACE.

BRICK-KILN.

SPECIFICATION forming part of Letters Patent No. 255,189, dated March 21, 1882.

Application filed August 12, 1881. (No model.)

To all whom it may concern:

Be it known that I, CLARK D. PAGE, of Rochester, Monroe county, New York, have invented a certain new and useful Improvement 5 in Brick-Kilns; and I do hereby declare that the following is a full, clear, and exact description of the same, reference being had to the accompanying drawings, in which—

Figure 1 is a longitudinal vertical section of 10 a kiln showing my improvement. Figs. 2 and 3 are cross sections respectively in lines *xx* and *yy*. Figs. 4 and 5 are a plan and end elevation of a portion of the endless apron at the discharge end of the kiln. Figs. 6 and 7 are 15 similar views of the car and its connections for removing the burned bricks.

My improvement relates to that class of kilns in which the green bricks are inserted in the top of the cupola and gradually fed downward, 20 being subject to heat during the whole passage, and are finally discharged in a finished state and ready for use. As fast as the bricks are removed at the bottom a new supply is added at the top, and the kiln is thus made perpetual 25 in its action. In general construction the kiln is similar to that patented by me March 29, 1864.

The invention consists in the construction and arrangement hereinafter more fully described and claimed.

In the drawings, *A* represents the staek, in which are located either two or four cupolas, *B*, *B*, two only being shown in the drawings. These cupolas stand side by side, divided only 35 by a division-wall, *C*. The upper portions of the cupolas are vertical; but the lower portions are curved on a large circle, forming chutes *B'*, *B'*, through which the bricks are finally discharged at their lower ends. The tops of the 40 chutes, below the fires, are covered with metal, which is in sections, so as to be removable.

D D D D are the furnaces, of which four are used with each pair of cupolas. These furnaces are arranged as shown in the cross-sectional 45 view, Fig. 2, two furnaces being used on each of two opposite sides, and consisting each of the usual arch and ash-pit, with suitable gratings, *a a*. Two of these furnaces—one on each side—lie centrally and open opposite to each

other into a common flue-space, *E*, which is divided centrally by the lower part of the division-wall *C*, which is narrowed or thinned in the arch. This wall forms a cross-division of the arch and breaks the currents which come in in opposite directions, deflecting them sidewise, 55 as indicated by the middle arrows in Fig. 2. From this point the currents pass on each side through ports *b b*, between piers *c c*, and enter the two cupolas on the inner sides. The other two furnaces are situated one on one side and 60 the other on the other side of the cross-center of the kiln, and have arches *F F*, which extend in some distance to cover the outer sides of the cupolas, and the hot currents from these arches pass through ports between piers *c' c'* and enter the cupolas on the outer side, counteracting those currents which enter from the central arch, *E*. By this means constant currents of 65 hot air enter the cupolas in two opposite directions, which meet and rise through the cupolas, equalizing the heat and producing a much more effective burning action on the brick than where the heat enters on one side only, as in ordinary kilns. This arrangement of the four furnaces—two on the central line 70 opposite each other and the other two outside, with corresponding arches inclosing the cupolas—is specially adapted to kilns having two 75 cupolas, and not to a single cupola.

G G are two removable doors at the top of 80 the kiln and above the cupolas, for the purpose of inserting the green bricks in the kiln. When the kiln is in operation these doors are tightly closed, as shown in Fig. 1.

H is a flue-passage in the top of the division-wall *C*, extending above the doors, and forming, in fact, a short supplementary chimney, which lies between the two cupolas, and connects therewith at the bottom by series of ports or passages *f f*, by which means a draft 85 from the cupolas is allowed through the flue when its top is uncovered.

I are two side flues or passages opposite the central flue, *H*, but lying outside of the cupolas, and communicating therewith by side 95 ports or passages, *g g*. The tops of these side flues come below the bottom of the doors *G G*. In the tops of the side flues are sliding damp-

ers or valves *h h*, and in the top of the central flue is a similar damper or valve, *i*. These dampers can be made to open or close the flues by sliding them in or out.

5 The operation of this part of the invention is as follows: The green bricks being inserted in the cupolas, the valve *i* in the central flue is closed, and the two valves *h h* in the side flues are opened, as shown in Fig. 1. The draft is then excluded from the central flue; but a portion passes up on each side through the side flues, *I*, and comes out at the top, close to the inner side of the doors *G G*. By this means the space next to the doors, and which is off-set from the cupola, obtains a quantity of the hot air that effectually removes what is known as the "water-smoke," the dampness arising from imperfect burning, and which in ordinary kilns is the cause of much difficulty, owing to 15 the chilling from the doors and the remoteness of the space from the direct draft. To renew the charge of bricks the valves *h h* are closed, and the valve *i* is opened, which cuts off the draft from the side flues and lets it on in the 20 center flue. By this means the hot air is drawn away from the doors, and when the doors are opened the cold air rushes in and no difficulty is experienced from the heat.

At the bottom of each chute is a valve, *k*, 30 which forms a cut-off, and outside of this is a projecting end, *l*, of the bottom of the chute, which enables the loose bricks to be picked off after the valve has been closed.

K is an endless apron or platform, which is 35 located at the bottom of each chute and runs on two sprocket-wheels, *j j*, as shown in Fig. 1. The apron consists of a series of cross-slats, *m m*, Figs. 4 and 5, having on their under side flanges *n n*, pivoted to links *o o*, the whole forming an 40 endless chain on each side, which runs on the sprocket-wheel and carries the slats. The bricks descending the chute fall on the apron and are carried along by the same to the discharge end of the chute. The slats are so near together 45 that they will not allow the bricks to pass through. The tops of the slats are provided with a series of longitudinal serrations or notches, *w*, extending their whole length, and which point backward against the passage of 50 the bricks, as shown in Fig. 5. The object of these serrations is to hold the bricks back and prevent their sliding forward, as they would do on a smooth surface. These serrations hold the bricks so that they only move with the 55 movement of the apron. On the under side of the upper length of the apron is a cam, *p*, having a shaft extending out through the side of the machine and operated by hand. The cam forms, in fact, a brake. The operator, by pressing it up, bears it against the weight of bricks 60 on top of the apron, and thus controls the movement of the apron. It is necessary to do this only in drawing a charge of the bricks. At other times, and while the burning is progressing, the apron is locked by the cam so that it 65 cannot move. The upper length of the apron also rests on rollers, which support it and ob-

viate friction in a great degree. Beneath the apron is a pit or chamber, *r*, for catching brick-dust and fragments which fall from above, and which otherwise would clog the apron. This pit is reached by a suitable door.

I is a car, having trucks or wheels which rest on rails. The inner end of the car is open, and it runs under the projecting end *l* of the chute and outside of it, as shown in Fig. 1. On the sides of the car are hooks or loops *s s*. *M M* are two arms pivoted to the sides of the chute, passing through the hooks *s s*, and provided at their outer ends with hook-heads *t t*, 80 as shown in Fig. 6.

The operation is as follows: The car is run under the end of the chute, as shown in Fig. 1. The valve *k* is drawn, which allows the bricks to run, and they discharge themselves 85 automatically into the car. As fast as the car fills it runs back under the pressure till the hook ends *t t* strike the hooks *s s*, which stops the car, the same being then loaded. The valve is then closed, the loose bricks having 90 been picked off from the projecting end of the chute, the arms *M M* are raised, releasing the car, which is then run off, and a new car is inserted in its place. In this manner very 95 rapid work is done. As fast as the finished bricks are drawn out at the bottom green 100 bricks are inserted at the top, the work being done by charges, and sufficient time being allowed between the charges for the bricks to be burned.

v is a thermometer which sits into the outer end of a flue, extending into the division-wall between the cupolas, and having branch flues which open into the cupolas, so that heat from the cupola may be conveyed to the thermometer, thereby showing the interior temperature 105 at all times.

Having thus described my invention, I claim—

1. In a brick-kiln, the combination, with the 110 two cupolas *B B*, of the four furnaces *D D D D*, arranged on opposite sides, two of said furnaces being located centrally opposite each other, communicating with an arch, *E*, which feeds the heated air to the inner sides of the 115 cupolas, and two being located one side the center and communicating with arches *F F*, which feed the heated air to the outer sides of the cupolas, as herein shown and described.

2. In a brick-kiln, the combination, with the 120 two cupolas *B B*, of the flue *H*, arranged centrally between the two cupolas, and the two side flues, *I I*, arranged outside the cupolas, said flues having ports or passages *f g g* at the bottom, communicating with the cupolas, 125 and provided with the valves *h h i* for controlling the draft through said flues, as herein shown and described.

3. In a brick-kiln, the apron *K*, composed of 130 cross-slats connected with endless chains at their ends, and provided with the longitudinal serrations or notches *w w*, as shown and described, and for the purpose specified.

4. The combination, with the endless apron

provided with serrated cross-slats, of the cam *p*, resting under the upper length of the apron and serving as a brake, as herein shown and described.

- 5 5. In a brick-kiln, the combination of the car *L*, provided with the hooks *s*, and the pivoted arms *M M*, having hook ends *t t* engaging with the hooks *s*, as herein shown and described.
- 10 6. In a brick-kiln, the combination, with the chute *B'*, provided with a valve, *k*, closing its

passage, of a car, *L*, open at its inner end and telescoping or passing under and outside the end of the chute when in position to receive the load, as herein shown and described. ¹⁵

In witness whereof I have hereunto signed my name in the presence of two subscribing witnesses.
